UNITED STATES PATENT OFFICE.

MAX C. MEYER, OF NEW YORK, N. Y.

GEM-SETTING.

1,064,152.

Specification of Letters Patent. Patented June 10, 1913.

Application filed October 23, 1909. Serial No. 524,221.

To all whom it may concern:

Be it known that I, MAX C. MEYER, a citizen of the United States, residing at New York city, borough of Brooklyn, county of 5 Kings, and State of New York, have invented certain new and useful Improvements in Gem-Settings, of which the following is a full, clear, and exact description.

- 10 This invention relates to improvements in gem settings and has among its objects to provide a form of setting which will afford particular protection to the gem, will be simple in construction and of such nature 15 as to fit the gem properly and afford protection against chipping, at the same time leaving the setting open to proper access of light and facilitating cleaning of the gem and the setting.
- 20 With these and incidental objects in view the invention consists in the novel constructions hereinafter described with reference to the accompanying drawings forming part of this specification, which drawings show a 25 preferred form of embodiment of my improvements.

In said drawings Figure 1 represents a side view of a finger ring embodying a gem setting having my improvements; Fig. 2 30 represents a side view of the same without the gem. Fig. 3 represents a top view without the gem, and Fig. 4 represents a top view with the gem.

I have shown my improvements more particularly as applied to a finger ring, but it will be understood that these inventions are 35 equally applicable to various forms of gem settings not only for rings but also for brooches and many other varieties of pieces 40 of jewelry and ornamental devices in which such settings may be used.

In Fig. 2 the ring is shown as having a shank 20, and at its upper portion two shoulders 21 with an intervening base portion 22. On this supporting base is mounted an open framework construction comprising a plurality of laterally circular bands 23, 45 24 and 25. These bands are preferably arranged horizontally in parallel planes with

their centers coinciding with the axis of the 50 whole setting, and are of variable diameter from the small diameter of band 23 to the large diameter of band 25. These bands are connected by a plurality of longitudinal posts 26. These posts are arranged on the 55 inside of the bands, and by being connected to the latter form an open framework construction for the setting. The gem 27 is placed on the interior of this basket-like construction, and is suitably held in place 60 by the upright posts 26 by bending over upon the gem the upper extremities of said posts. Of course these posts 26 diverge outward in accordance with the increasing 65 diameters of the laterally circular bands.

It results in this construction that the girdle of the stone or gem is protected from breaking or chipping, the additional light which is allowed to enter the space around the gem materially improves the appearance 70 of the stone, and the open nature of the construction also makes it very easy to clean the setting and the gem. Moreover, the formation of the setting is such as to more readily conform to the shape of gems having 75 a particular cutting, such as diamonds and other similar stones; and the stone is more securely held in place under the protection of the circular bands separating the vertical posts.

Although the form of construction herein shown and described constitutes a preferred form of embodiment of my improvement, yet it is to be understood that various other forms of construction might be utilized, all 85 coming within the scope of the claims which follow.

What is claimed is:

1. A gem setting comprising an article of jewelry constituting a supporting base, and 90 an open framework mounted and attached to the base, consisting of a plurality of posts adapted to engage and hold a gem at their upper ends, and a plurality of horizontal bands closely encircling and fastened to the 95 posts.

2. A gem setting comprising an article of jewelry constituting a supporting base, and

attached thereto an open framework composed of a plurality of posts spaced equidistantly apart and adapted to engage and hold a gem at their upper ends, and a plurality of horizontal circular bands closely encircling and fastened to the posts.

In testimony whereof I affix my signa-

ture in the presence of two subscribing witnesses.

MAX C. MEYER.

Witnesses:

LILIAN E. WEINSTOCK,
ISAAC L. MEYER.
